ARMCHAIR

Giovanni Offredi, Milan, Italy, assignor to Fratelli Saporiti Industria Arredamenti di Saporiti Sergio e Giorgio S.N.C., Besnate (Varese), Italy

Filed Mar. 20, 1973, Ser. No. 343,008

Claims priority, application Italy Sept. 22, 1972

Term of patent 14 years

Int. Cl. D6—01

U.S. Cl. D6—71

FIG.1

FIG.3

FIG. 1 is a front perspective view, looking somewhat downwardly, of an armchair embodying my new design;

FIG. 2 is a side-elevational view of the chair, the side opposite being a mirror image of the side shown.

FIG. 3 is a rear-elevational view thereof.

I claim:

The ornamental design for an armchair, as shown and described.
